(57) **CLAIM**

The ornamental design for a portable terminal, as shown and described.

DESCRIPTION

FIG. 1 is a front perspective view of a portable terminal showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the encircled portion A as shown in FIG. 4.

The broken lines shown in the figures that are immediately adjacent to the shaded areas and define regions that are consistently unshaded, represent the bounds of the claim, while all other broken lines, including those within the broken line boundaries, those that have been shaded through, and the features shown within the non-claimed unshaded front and rear surfaces are directed to non-claimed environment; the broken lines form no part of the claimed design.

The dot-dash broken lines encircling a portion of the claimed design that are illustrated in an enlargement form no part of the claimed design.

The shade lines in the figures show contour and not surface ornamentation.
